UNITED STATES PATENT OFFICE.

WILLIAM E. PRINDLE, OF LONDON, OHIO, ASSIGNEE TO BUCKEYE DRIER COMPANY,
OF LONDON, OHIO, A FIRM COMPOSED OF WILLIAM E. PRINDLE AND H. M. CHANEY.

MECHANICAL ROTARY DRIER.

1,222,244.

Specification of Letters Patent. Patented Apr. 10, 1917.

Application filed August 5, 1915. Serial No. 43,786.

To all whom it may concern:

Be it known that I, WILLIAM E. PRINDLE, a citizen of the United States, residing at London, in the county of Madison and State 5 of Ohio, have invented certain new and useful Improvements in Mechanical Rotary Driers, of which the following is a specification.

The present invention relates to mechanical rotary driers and aims to particularly 10 provide a construction calculated to guard against the over drying or burning of the material being acted upon.

One of the objects of my invention resides 15 in the provision of a structure to be used in connection with a drier employing an inner cylinder within an outer cylinder, this inner cylinder being the one into which the drying gases or heated air is initially introduced, 20 this structure being such that the material is prevented from being cascaded directly in front of the open end of the inner cylinder or that portion of the inner cylinder from which the highly heated gases or air issues. 25 In this manner, the material, should it be in a partially dry state or comparatively dry state, will be prevented from being scorched or over-heated. It must also be remembered that some materials are of an inflammable 30 nature and, therefore, this structure is provided to guard against the possibility of this material being ignited.

A further object of my invention resides 35 in the combination of an inner cylinder and an outer cylinder, this inner cylinder being located in the rear portion of the outer cylinder and being arranged to conduct the heated products in a direction opposite to the travel of the material through the outer cylinder, with means for permitting the inflow 40 of an auxiliary quantity of drying products such as air or gas into the space formed between the inner and outer cylinders. In the absence of this auxiliary supply, this space 45 is what is known as a more or less dead space, there being no appreciable flow of air at this point and consequently the radiated heat cannot perform its function as efficiently as it would in the presence of a slight draft or flow of air.

A still further object of my invention resides in an outer cylinder construction 50 wherein the fore part of this cylinder is divided into a series of compartments into which the material being dried is introduced

in the early part of its passage through the cylinder. These compartments are resorted to in order that the material may be more thoroughly cascaded as the outer cylinder is rotated and in this manner the various particles comprising the bulk are subjected to a greater amount of air than would be the case were the whole in a single compartment.

A still further object of my invention resides in a conveyer structure located in the 65 fore part of the outer cylinder for feeding the material into the various compartments after its introduction into the outer cylinder through the usual type of supply feeding means.

The preferred embodiment of my invention is shown in the accompanying sheets of drawings, in which similar characters of reference designate corresponding parts, and in which:

Figure 1 is a central vertical section through my drier.

Fig. 2 is a section taken on line 2-2 of Fig. 1.

Fig. 3 is a section taken on line 3-3 of Fig. 1,

Fig. 4 is a section taken on line 4-4 of Fig. 1,

Fig. 5 is a section taken on line 5-5 of Fig. 1, and

Fig. 6 is an end view looking from the left of Fig. 1 with the front ring removed.

In these drawings, the outer cylindrical casing is designated in its entirety by the reference numeral 1, although this casing is made in various sections as will be presently related. This casing is also preferably mounted so as to rest at an incline to the horizontal and is directly supported by means of annular tires 2 upon rollers 3 preferably located at suitable distances at each side of a central vertical plane and which are mounted upon abutments 4. Rotary motion is imparted to the outer cylinder 1 through the medium of an annular spur gear 5 carried at one end of the casing of the cylinder, this spur gear being designed to mesh with a spur pinion 6 upon a shaft 7, which shaft is driven in any desirable manner from any suitable source of power supply.

In the rear portion of this outer cylinder there is mounted an inner cylinder 8 preferably extending toward the inlet portion of the outer cylinder a distance only to ap-

proximately cover that portion which is normally occupied by the dried or nearly dried material as it passes to the conveyer 9 located below the rear open end of this outer cylinder. The distance this inner cylinder extends into the outer cylinder must, of course, be determined, its prime function being to avoid direct contact of the heated products of combustion with the material being treated, reliance being had to a large degree upon the radiated heat from this cylinder to complete the drying. The distance this cylinder extends into the outer cylinder may be stated as representing the final stage of the drying operation and prevents the hottest gases from contacting with the driest material. This inner cylinder is mounted to rotate with the outer cylinder by means of arms 10 and 11 arranged in spider relation, the construction being such that the required compensation between the two cylinders due to expansion and contraction, may be had. The forward end of this inner cylinder is further provided with a flaring hood 12, the flare being provided to prevent the access of the material in case some of it should drop from the upper portion of the outer cylinder to the inner portion of the inner cylinder and is further provided to diffuse the heated products of combustion in a more or less degree. This inner cylinder is also preferably lined with some type of refractory material as is shown at 13 this refractory lining being used so that the heated products of combustion do not come into direct contact with the metallic wall of the inner casing, which would then naturally become heated to a very high degree and which would then be more or less liable to cause a burning or scorching of the material being dried should this material come in contact with the metal portion of this inner cylinder.

Located adjacent the delivery end of the drier as a whole, is a hot air producer 14, this producer being in the form of a furnace and is provided with the usual type of grate bars 15 and outlet flue 16, which latter flue connects with the flue pipe 17 also preferably lined with refractory material as indicated at 18. The flue pipe 17 is then connected with the inner cylinder in any preferred manner, it being essential only that this connection should be such that the inner cylinder proper be capable of rotation, while the flue pipe 18 is preferably held in a stationary position. The distance between the heat producer 14 and the discharge end of the drier as a whole is closed to the atmosphere to prevent escape of the dried material in the form of dust and also to prevent the entrance of foreign material at this point by means of a stationary hood 19 shaped to conform to the outer cylinder and to support the conveyer 9 already referred to, this hood being supported in any desired manner upon supporting standards 20. This conveyer 9 is designed to conduct the dry material laterally of the drier as a whole, as is shown in Fig. 4 and it may lead to any desired delivery point. The furnace or heat producer 14 is further provided with a hot air space, as is shown at 21, this hot air space being located above the arch 22 and being provided with an inlet portion 23 of any desired form. The rear wall of the furnace is provided with an opening as is shown at 24 in Fig. 5 and this opening is connected by means of a flue 25 with the rear wall of the hood 19 and in this manner this flue 25 also is in communication with the space formed between the inner and outer cylinders. It will thus appear that I have provided a construction for introducing an auxiliary air support into the rear portion of the cylinder and into that portion of the drier as a whole, which relies upon its drying action principally upon radiated heat. By the introduction of this auxiliary air, a direct draft is produced and the air or heated products of combustion thus introduced, are also capable of absorbing and carrying moisture in suspension to complete the drying operation. Further, this draft will more or less temper the heat at this point, since the radiation from the inner cylinder may become expansive due to the high temperature of the gases issuing from the furnace 14.

Wet material is introduced to the front end of the outer cylinder by means of a feed spout 26 carrying a hopper 27 at its upper end and rigidly mounted in connection with the vapor bonnet 28. This vapor bonnet forms a stationary portion for closing the front end of the outer cylinder 1 and is so formed that it has rotating contact with the front ring 29 rigidly mounted in connection with the cylinder 1 itself. This vapor bonnet 28 also has a central opening formed therein to which is connected the fan or suction device connection 30, leading to the fan or other suitable type of suction device shown generally at 31.

The front end of this cylinder 1 is also provided with a series of spiral baffles or flights 32, these flights being located in co-operative relation with the feed spout 26 and being attached at their inner ends to radially arranged flights in the manner shown at 33. The number of these radially arranged flights preferably agree with the number of compartments 34 formed immediately to the rear of the flights 32. In other words, in the present drawings, the portion of the cylinder 1 immediately to the rear of the spiral flights 32 is shown as being formed into four compartments by means of the radially arranged plates 35,

all as clearly shown in Fig. 2. Each of these compartments is provided with a series of baffles 36, these baffles being constructed of angle iron or of combined angle iron and knuckle plate as may be desired and as is shown. The flights 32 are so arranged that as the material is fed into the front end of the cylinder, it is also fed into the various compartments as they pass their lowermost position. Therefore, each of the compartments contains a portion of the introduced wet material and this wet material is cascaded by means of the baffles 36. I resort to the use of a plurality of compartments, since the drying action is more efficient where the material is dried in small quantities than where it is cascaded in one entire bulk, because in the former operation this material may be considered as being divided more evenly than where the entire mass is cascaded in one bulk. After this portion of the drier is traversed, the material enters the portion 37 which consists of a section not divided up into compartments but provided with a series of angle iron baffle plates 38 arranged in staggered relation, as is shown. In this portion of the drier the entire bulk is cascaded, but it is at this point that it comes into contact with gases which are warmer than those gases encountered at the extreme rear of the casing 1, since this point is closer to the point of emission of these gases from the inner cylinder 8.

In order to prevent the material from being cascaded directly in front of the emitted gases from the inner cylinder 8, I have provided a section 39 which section has a series of baffles or flights 40 arranged in spiral array. Therefore, instead of the material being cascaded in the same manner as it is in the compartments and in the section 37, it is moved through the outer cylinder more on the order of a spiral conveyer and in this manner is not carried up the side walls and adjacent the top to be dropped in front of the open end of the inner cylinder 8 as would be the case should the use of flights of the type shown at 38 be resorted to.

The remaining portion of the outer cylinder may be provided with flights of the type shown at 41 or any other preferred type of flight, the remaining portion of the drying operation being accomplished principally by the radiated heat and the draft caused by the inflow of heated air over the top of the furnace 14. However, this material has practically completed its drying operation before it enters the section to the right of the section 39.

The operation of my device is as follows: Rotation is given the outer cylinder 1 by means of any suitable type of driving mechanism after the heat producing unit has been

set in operation and likewise the suction device 31. The wet material is then introduced into the interior of the outer cylinder by passage through the feed spout 26 and the rotation of this outer cylinder in connection with the spirally arranged flights 32 will feed this introduced material into the various compartments 34 where it is cascaded due to the lifting blade structure as is shown and thereby mingles very thoroughly with the heated products of combustion admitted through the heat producer 14. This introduced material will travel toward the right of the cylinder because of the inclination at which this cylinder is set and will ultimately discharge into the conveyer 9 at the extreme end of the conveyer. During its passage, this material leaves the compartment 34 and enters the section 37 where it is cascaded in bulk. Here it is forced into the section 39 containing the spiral arrangement of flights 40 and by means of these flights the material is prevented from dropping and being cascaded directly in front of the open end of the inner cylinder 8 through which the highly heated gases from the furnace 14 issue. By this arrangement this material is prevented from being scorched and burned and is effectively transmitted to that portion of the drier using radiated heat principally in the drying operation. In order that this inner cylinder may not itself become burnt due to the high temperature of the products of combustion, I have lined the same with a refractory lining as is shown and this refractory lining further serves the purpose of preventing too excessive a radiation to cause a burning of the material being cascaded at this point. To insure the flow of heated air at this point, I have provided a conduit 25 which connects with the space 21 formed in the upper portion of the furnace and by this means an auxiliary air supply is given. This air supply may be used to temper the heat at this point of the outer cylinder and may further be used to insure a draft through the outer cylinder at this point. The suction device 31 insures the flow of air through the drier as a whole and it is this air which carries the moisture extracted from the material in suspension.

From the foregoing, it will be apparent that I have provided a type of furnace which may be used for drying material of a highly inflammable nature and this drying operation may be carried on most efficiently.

What I claim, is:

1. A rotary drier comprising an outer cylinder provided adjacent its front end with a hot air outlet, means for feeding material to the front end of said cylinder, a hot air producer, an inner cylinder within

and in communication with said outer cylinder and communicating at its rear end with said producer, said inner cylinder extending into the rear portion only of said outer cylinder a distance to prevent direct contact of the heated gases with the material after it has passed through said outer cylinder a distance to be in a comparatively dry state, a suction device connected to said hot air outlet to cause a flow of hot air in a direction opposite to the travel of the material through said outer cylinder, and means for permitting an inflow of air into the rear of said outer cylinder and in the space between it and said inner cylinder.

2. A rotary drier comprising an outer cylinder provided adjacent its front end with a hot air outlet, means for feeding material to the front end of said cylinder, a hot air producer, an inner cylinder within and in communication with said outer cylinder and communicating at its rear end with said producer, said inner cylinder extending into the rear portion only of said outer cylinder a distance to prevent direct contact of the heated gases with the material after it has passed through said outer cylinder a distance to be in a comparatively dry state, a suction device connected to said hot air outlet to cause a flow of hot air in a direction opposite to the travel of the material through said outer cylinder, and auxiliary means for introducing heated air from said furnace into the rear portion of the space formed between said inner and outer cylinders.

3. A rotary drier comprising an outer cylinder provided adjacent its front end with a hot air outlet, means for feeding material to the front end of said cylinder, a hot air producer, an inner cylinder within and in communication with said outer cylinder and communicating at its rear end with said producer, said inner cylinder extending into the rear portion only of said outer cylinder a distance to prevent direct contact of the heated gases with the material after it has passed through said outer cylinder a distance to be in a comparatively dry state, a suction device connected to said hot air outlet to cause a flow of hot air in a direction opposite to the travel of the material through said outer cylinder, a hot air space other than its combustion chamber formed in said hot air producer independent of the operation of said producer, and a conduit connecting said space and the space formed between said inner and outer cylinders.

4. A rotary drier comprising an outer cylinder provided adjacent its front end with a hot air outlet, means for feeding material to the front end of said cylinder, a hot air producer, an inner cylinder within and in communication with said outer cylinder and communicating at its rear end with said

producer, said inner cylinder extending into the rear portion only of said outer cylinder a distance to prevent direct contact of the heated gases with the material after it has passed through said outer cylinder a distance to be in a comparatively dry state, a refractory lining for said inner cylinder, a suction device connected to said hot air outlet to cause a flow of hot air in a direction opposite to the travel of the material through said outer cylinder, and means for permitting an inflow of air into the rear of said outer cylinder and in the space between it and said inner cylinder.

5. A rotary drier comprising a rotatable outer cylinder provided with a hot air outlet, a feed means communicating with the interior of said cylinder, an inner cylinder in communication with and within said outer cylinder, a hot air producer connected to one end of said inner cylinder, and means for preventing the cascading of the material in front of the open end of said inner cylinder as said outer cylinder rotates.

6. A rotary drier comprising a rotatable outer cylinder provided with a hot air outlet, a feed means communicating with the interior of said cylinder, an inner cylinder in communication with and within said outer cylinder, a hot air producer connected to one end of said inner cylinder, baffles on the interior of said outer cylinder, and a second set of baffles on the interior of said outer cylinder adjacent the open end of said inner cylinder arranged to prevent the dropping of the material directly past the open end of the inner cylinder as the outer cylinder is rotated.

7. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear with said producer, said inner cylinder extending into the rear portion only of said outer cylinder a distance to prevent direct contact of the heated gases with the material after it has passed through said outer cylinder a distance to be in a comparatively dry state, a suction device connected to said hot air outlet to cause a flow of hot air in a direction opposite to the travel of the material through said outer cylinder, and means for preventing the cascading of the material directly in front of the open end of said inner cylinder as said outer cylinder is rotated.

8. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear with said

producer, said inner cylinder extending into the rear portion only of said outer cylinder a distance to prevent direct contact of the heated gases with the material after it has 5 passed through said outer cylinder a distance to be in a comparatively dry state, a suction device connected to said hot air outlet to cause a flow of hot air in a direction opposite to the travel of the material 10 through said outer cylinder, and a series of spirally arranged baffles on the inside of said outer cylinder arranged to prevent the cascading of the material directly in front of the open end of said inner cylinder as said 15 outer cylinder is rotated.

9. A rotary drier comprising a rotatable outer cylinder provided with a hot air outlet, a feed means communicating with the interior of said cylinder, a hot air producer, 20 an inner cylinder being also in communication with said producer, and a series of longitudinally extending compartments formed in said outer cylinder in the space not occupied by said inner cylinder.

25 10. A rotary drier comprising a rotatable outer cylinder provided adjacent its front end with a hot air outlet, means for feeding material into the front end of said cylinder, a hot air producer, an inner cylinder within 30 and in communication with said outer cylinder and communicating at its rear with said producer, said inner cylinder extending into the rear portion only of said outer cylinder a distance to prevent direct contact of the 35 heated gases with the material after it has passed through said outer cylinder a distance to be in a comparatively dry state, a suction device connected to said hot air outlet to cause a flow of hot air in a direction 40 opposite to the travel of the material through said outer cylinder, a series of spirally arranged baffles on the inside of said outer cylinder arranged to prevent the cascading of the material directly in front of the 45 open end of said inner cylinder as said outer cylinder is rotated, and a series of spiral baffles located in said outer cylinder between said feed means and said compartments to direct the material into the 50 compartments.

11. A rotary drier comprising a rotatable outer cylinder provided adjacent its front end with a hot air outlet, means for feeding material into the front end of said cylinder, 55 a hot air producer, an inner cylinder within and in communication with said outer cylinder and communicating at its rear with said producer, said inner cylinder extending into the rear portion only of said outer cylinder 60 a distance to prevent direct contact of the heated gases with the material after it has passed through said outer cylinder a distance to be in a comparatively dry state, a suction device connected to said hot air 65 outlet to cause a flow of hot air in a direc-

tion opposite to the travel of the material through said outer cylinder, a series of spirally arranged baffles on the inside of said outer cylinder arranged to prevent the cascading of the material directly in front of the open end of said inner cylinder as said outer cylinder is rotated. 70

12. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear with said producer, a series of longitudinally extending compartments formed in said outer cylinder in the space not occupied by said inner cylinder, said inner cylinder extending into the rear portion only of said outer cylinder, and a suction device connected to said hot air outlet to cause a flow of hot air in a direction opposite to the travel of the material through said outer cylinder. 80

13. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear with said producer, a series of longitudinally extending compartments formed in said outer cylinder in the space not occupied by said inner cylinder, said inner cylinder extending into the rear portion only of said outer cylinder, a suction device connected to said hot air outlet to cause a flow of hot air in a direction opposite to the travel of the material through said outer cylinder, and means for permitting an inflow of auxiliary air into the rear of said outer cylinder and in the space between it and said inner cylinder. 90

14. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear end with said producer, said inner cylinder extending into the rear portion of said outer cylinder a distance to prevent direct contact of the heated gases with the material after it has passed through said outer cylinder a distance to be in a comparatively dry state, 105 a series of longitudinally extending compartments formed in said outer cylinder in the space not occupied by said inner cylinder, means for preventing the cascading of the material directly in front of the open end of said inner cylinder as said outer cylinder is rotated, and a suction device connected to said hot air outlet to cause the flow of hot air in a direction opposite to the travel of material through said outer cylinder. 110

15. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear with said producer, said inner cylinder extending into the rear portion only of said outer cylinder a distance to prevent direct contact of the heated gases with the material after it has passed through said outer cylinder a distance to be in a comparatively dry state, a suction device connected to said hot air outlet to cause the flow of hot air in a direction opposite to the travel of material through said outer cylinder. 120

16. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear with said producer, said inner cylinder extending into the rear portion only of said outer cylinder a distance to prevent direct contact of the heated gases with the material after it has passed through said outer cylinder a distance to be in a comparatively dry state, a suction device connected to said hot air outlet to cause the flow of hot air in a direction opposite to the travel of material through said outer cylinder. 125

130

15. A rotary drier comprising a rotatable outer cylinder provided adjacent its front end with a hot air outlet, means for feeding material into the front end of said cylinder, a hot air producer, an inner cylinder within and in communication with said outer cylinder and communicating at its rear end with said producer, said inner cylinder extending into the rear portion of said outer cylinder a distance to prevent direct contact of the heated gases with the material after it has passed through said outer cylinder a distance to be in a comparatively dry state, a series of longitudinally extending compartments formed in said outer cylinder in the space not occupied by said inner cylinder, means for preventing the cascading of the material directly in front of the open end of said inner cylinder as said outer cylinder is rotated, a suction device connected with said hot air outlet to cause the flow of hot air in a direction opposite to the travel of material through said outer cylinder, and means for permitting an inflow of air into the rear of said outer cylinder and in the space between it and said inner cylinder.
16. A rotary drier comprising a rotatable outer cylinder provided adjacent its front end with a hot air outlet, means for feeding material into the front end of said cylinder, a hot air producer, an inner cylinder within and in communication with said outer

cylinder and communicating at its rear with said producer, said inner cylinder extending into the rear portion of said outer cylinder a distance to prevent direct contact of the heated gases with the material after it has passed through said outer cylinder a distance to be in a comparatively dry state, a series of longitudinally extending compartments formed in said outer cylinder in the space not occupied by said inner cylinder, a series of spiral baffles located in said outer cylinder between said feed means and said compartments to direct the material into the compartments, a second series of spiral baffles on the inside of said outer cylinder arranged to prevent cascading of the material directly in front of the open end of said inner cylinder as said outer cylinder is rotated, auxiliary means for introducing heated air from said furnace into the rear portion of the space formed between said inner and outer cylinders, and a suction device connected to said hot air outlet to cause a flow of air in a direction opposite to the travel of the material through said outer cylinder.

In testimony whereof I affix my signature in presence of two witnesses.

WILLIAM E. PRINDLE.
